Patented Feb. 22, 1921.

Inventor:
Charles W. Arnum

By Jones, Aldington, Ernest Seibold
Atty. S.

UNITED STATES PATENT OFFICE.

CHARLES W. ARNUM, OF CHICAGO, ILLINOIS.

SILVER-RIBBON ICICLE.

1,368,996.

Specification of Letters Patent. Patented Feb. 22, 1921.

Application filed April 28, 1919. Serial No. 293,252.

To all whom it may concern:

Be it known that I, CHARLES W. ARNUM, a citizen of the United States, residing at Chicago, in the county of Cook and State of Illinois, have invented new and useful Improvements in Silver-Ribbon Icicles, of which the following is a full, clear, concise, and exact description, reference being had to the accompanying drawing, forming a 10 part of this specification.

My invention relates to improvements in silver ribbon icicles and has for its object the production of a new article of manufacture that is capable of reflecting light and 15 giving the appearance of being icicles.

A further object is the production of an article that can be cheaply formed and gives the desired results.

These and such other objects as may here- 20 inafter appear are attained by my device, an embodiment of which is illustrated in the accompanying drawing in which—

A represents a plurality of narrow strips of tin foil bound or secured together by a 25 containing strip or band B.

The icicle strips A, are formed by cutting sheets of tin foil of any desired size, the operation being performed by using a series of cutting blades set as closely together as 30 necessary in order to produce strips of the desired width. As the strips are cut they are crinkled or roughened as rather imper- fectly shown in the drawings but the entire surface of the strip is definitely rough-

ened or crinkled so as to form a plurality 35 or multiplicity of reflecting surfaces occupying different planes with respect to adjacent surfaces.

The result of this form or shape of construction is that light thrown on this 40 crinkled surface is reflected in every direction.

In the use of my article the strips of material are hung or thrown irregularly over the article to be decorated, for instance, a 45 Christmas tree. The lights from candles or bulbs on the tree as well as from the lights in the room are reflected in every direction giving the tree the appearance of being covered with frost or icicles. 50

It is of course understood that my invention may embody different forms which if made of roughened tin foil or like make, comes well within the spirit of my invention.

Having thus described my invention, what 55 I claim as new and desire to secure by Letters Patent is—

As a new article of manufacture, a strip of tin foil formed with a roughened face, said face comprising a plurality of intersecting surfaces occupying different angles with respect to each other and capable of reflecting in every direction, rays of light thrown on such surface. 60

In witness whereof, I have hereunto sub- 65 scribed my name.

CHAS. W. ARNUM.
